UNITED STATES PATENT OFFICE

140,933

DESIGN FOR A SAFETY HOLDER FOR BABIES

Margaret R. Koster, Brooklyn, N. Y.

Application November 8, 1943, Serial No. 111,623

Term of patent 14 years

(Cl. D3—17)

To all whom it may concern:

Be it known that I, Margaret R. Koster, a citizen of the United States, residing at 483 14th Street, Brooklyn, in the county of Kings, city and State of New York, have invented a new, original, and ornamental Design for a Safety Holder for Babies, of which the following is a specification, reference being had to the accompanying drawing, forming part thereof.

Fig. 1 is a plan view of a safety holder for babies showing my new design, and
Fig. 2 is a front elevational view thereof as it appears when in use.

I claim:

The ornamental design for a safety holder for babies, as shown.

MARGARET R. KOSTER.
